His Attorney.

UNITED STATES PATENT OFFICE.

CHARLES P. RANDOLPH, OF OAK PARK, ILLINOIS, ASSIGNOR TO EDISON ELECTRIC APPLIANCE COMPANY, INCORPORATED, OF CHICAGO, ILLINOIS, A CORPORATION OF NEW YORK.

ELECTRIC HEATER.

Application filed November 30, 1923. Serial No. 677,868.

To all whom it may concern:

Be it known that I, CHARLES P. RANDOLPH, a citizen of the United States, residing at Oak Park, in the county of Cook, 5 State of Illinois, have invented certain new and useful Improvements in Electric Heaters, of which the following is a specification.

My invention relates to electric heaters, 10 more particularly to portable electric heaters, and has for its object the provision of means for causing the heater in case it is overturned to automatically assume a position such that the heat radiations are directed upward.

More specifically, my invention relates to 15 portable electric heaters of the radiant type provided with a reflector for directing the heat radiations in one general direction. As 20 usually constructed such a heater consists of a heating unit mounted in a reflector, the whole being supported on a suitable base. Due to unavoidable features of construction, such a heater may be overturned 25 accidentally, or otherwise placed in a position such that the heat radiations are directed downward. In such a position it constitutes a fire hazard. Various schemes have 30 been proposed for overcoming this fire hazard. One of these schemes consists in providing an off center weight for the base which causes the heater when overturned to roll over to a position in which the heat 35 radiations are directed upward. Such a scheme is shown in Patent 1,481,993 to H. E. Strunk, dated October 17, 1922.

In carrying out my invention I provide 40 a base for the heater of such shape that the heater is caused to roll to a safe position when overturned. I may also provide a weight for making this action more effective.

For a more complete understanding of 45 my invention reference should be had to the accompanying drawing in which Fig. 1 is a perspective view of an electric heater embodying my invention; Fig. 2 is an elevation view of the heater overturned to a position in which the heat radiations are directed 50 downward; while Fig. 3 is a view showing the position in which the heater finally comes to rest after being overturned.

Referring to the drawing, I have shown 55 my invention in one form as applied to a portable electric radiant heater comprising

a suitable electric heating unit 10 which is mounted in such position with relation to a reflector 11 that the heat radiations are reflected in a common direction. The heating unit and reflector are mounted on a supporting base 12. A pivotal adjustable connection 13 is provided with the base so that the heater may be adjusted and locked to throw the heat radiations at the desired vertical angle above or below horizontal. The terminals of the heating unit 10 are brought out inside a suitable housing 14 provided with means whereby the heater may be connected to an electric circuit in any well known manner, as for instance by means of a permanently attached cord or by an attachment plug. A wire guard 15 is provided over the face of the reflector. This guard is preferably bulged outward as shown in the drawing so that its outline is oval or spherical. The guard is provided to improve the appearance of the heater and protect it and also to overcome to a certain extent the tendency of the heater to remain face downward when overturned.

The base 12 is provided with a pointed or oval shaped extension 16 which extends toward the front of the heater in the direction of the heat radiations.

The back portion 17 of the base takes the 85 form of a smooth curve. As shown the base is acorn shaped. It may, however, have various other shapes, such as oval or elliptical.

As thus constructed, it will be observed 90 that in case the heater is overturned, face downward, to the position illustrated in Fig. 2, it will be very unstable due to the shape of the base and also of the guard 15. It will be observed that in this position the heater rests on the guard and on the point of the extension 16 of the base. The heater thus has a tendency to roll over. In fact, it is practically impossible to balance it in the position shown in Fig. 2, and in case it were so balanced any jar would be sufficient to unbalance it and cause it to roll over on its back to a safe position as shown in Fig. 3. It will be understood that the base 12 is relatively heavy with respect to other parts of the heater and by reason of its weight has sufficient momentum to carry the heater over the edge of the reflector to the position shown in Fig. 3.

For the purpose of giving the heater a 110

greater momentum as it rolls, and also to make it more unstable when in the position shown in Fig. 2, a weight 18 may be provided on the base. This weight is preferably placed off center, that is, at one side of the vertical center line X-Y of the base when in the position shown in Fig. 2. It may be formed or cast integral with the base as shown, or it may be a separate part 10 secured to the base. I have found, however, that the weight 18 is not absolutely necessary since the unbalancing of the heater due to the elongated extension 16 of the base, is ordinarily sufficient to cause the 15 heater to roll over to the position shown in Fig. 3, especially under the conditions existing when the heater is accidentally knocked over.

When the weight 18 is not used the heater 20 may roll in a clockwise direction from the position shown in Fig. 2 to the position shown in Fig. 3, or it may roll in the opposite direction to a similar position. The direction of roll will depend on which of the 25 two directions the heater happens to be more unstable in after being overturned. When the weight 18 is used the heater will tend to roll when overturned to the position shown in Fig. 3 and will always assume this position. In case it should start to roll in a counter-clockwise direction, the effect of the 30 weight will be sufficient to carry it completely over to the position shown in Fig. 3. When the weight is not used, the heater will 35 not roll completely over when rolling in a counter clockwise direction but will come to rest in a position corresponding to Fig. 3.

While I have described my invention as embodied in concrete form and as operating 40 in a specific manner in accordance with the provisions of the patent statutes, it should be understood that I do not limit my invention thereto, since various modifications thereof will suggest themselves to those 45 skilled in the art without departing from the spirit of my invention, the scope of which is set forth in the annexed claims.

What I claim as new and desire to secure by Letters Patent of the United States, is:—

50 1. An electric heater comprising a radiant electric heating unit, a reflector for directing the heat radiated by said unit, and a base for said unit and reflector so shaped that the

heater when overturned assumes a position in which the heat radiations are directed upward. 55

2. An electric heater comprising a radiant electric heating unit, a reflector for directing the heat radiated by said unit, an outwardly curved guard for said reflector, and a base for said unit and reflector so shaped 60 that the heater when overturned assumes a position in which the heat radiations are directed upward.

3. An electric heater comprising a radiant electric heating unit, a reflector for directing the heat radiated by said unit, a protruding guard for said reflector, and a base for said unit and reflector having an extension 65 extending in the direction of the heat radiations, said base being otherwise so shaped 70 that the heater when overturned assumes a position in which the heat radiations are directed upward.

4. An electric heater comprising a radiant electric heating unit, a reflector for directing the heat radiated by said unit, and a supporting base for said unit and reflector provided with an oval shaped extension 75 pointing in the direction of the heat radiations 80 whereby the heater is unstable when overturned to any position such that the heat is directed downward.

5. An electric heater comprising a radiant electric heating unit, a reflector for directing the heat radiated by said unit, a protruding guard for said reflector and an oval 85 like supporting base for said heating unit 90 and reflector pointing in the direction of the reflected heat, whereby the heater when overturned assumes a position such that the heat is directed upward.

6. An electric heater, comprising a radiant electric heating unit, a reflector for directing the heat radiated by said unit, an outwardly curved guard for the front of said reflector, an acorn shaped base for said reflector pointing in the direction of the reflected heat whereby the heater when overturned tends to roll over to a position such 100 that the heat is directed upward, and a weight on said base.

In witness whereof, I have hereunto set my hand this 24th day of November, 1923.

CHARLES P. RANDOLPH.
